UNITED STATES PATENT OFFICE.

FRED R. BARBOUR, OF LOS ANGELES, CALIFORNIA.

ROUTE INDICATOR.

Application filed April 11, 1922. Serial No. 551,707.

To all whom it may concern:

Be it known that I, FRED R. BARBOUR, a citizen of the United States, residing at Los Angeles, in the county of Los Angeles and State of California, have invented a new and useful Route Indicator, of which the following is a specification.

This invention aims to provide novel means whereby motion may be imparted electrically to a signal arm, or semaphore, the device being of peculiar utility in connection with motor vehicles, to secure a proper observance of traffic laws.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention, the semaphore being lowered, and the lid for the casing being removed from the casing; Figure 2 shows in elevation, a device constructed in accordance with the invention, the semaphore being raised, and the lid for the casing being removed; Figure 3 is a section on the line 3—3 of Figure 2; and Figure 4 is a sectional detail disclosing a portion of the casing.

In carrying out the invention, there is provided a support or casing 1 adapted to be mounted on a vehicle, no means for mounting the support on a vehicle being shown, since these details will depend on the make of the automobile, and other conditions.

The casing or support 1 includes a box-like body 2 provided with studs 3 on which is mounted a carrier or plate 4, the same preferably being made of insulating material. A lid 5 for the body 2 is provided, and is mounted on the outer ends of the studs 3, the lid being held on the studs by nuts 6 threaded on the studs. A bracket 7 is mounted on the plate 4 and is provided with a flange 8 supporting an electro-magnet 9, the ends of the winding 10 of the

magnet being prolonged through an opening 11 in the bottom of the body 2. A depending first lever 12 is fulcrumed at its upper end as shown at 14 on the plate 4 and is responsive to the electro-magnet 9. The device includes an upstanding second lever 15 fulcrumed at its lower end as shown at 16 on the plate 4. The lever 15 is offset intermediate its ends to form a shoulder 17, the shoulder being provided with an opening 18 wherein a reduced finger 19 on the lower end of the first lever 12 is loosely received, one end of the lever 15 being, therefore, connected pivotally with the lever 12 intermediate the ends of the lever. At its upper end the second lever 15 is supplied with an outwardly projecting arm 20 having an upstanding flange 21. A semaphore arm or signal 22 is mounted pivotally at 23, intermediate its ends, on the plate 4. The semaphore 22 operates in a slot 24 in the edge of the body 2 of the casing 1. In its inner end, the semaphore 22 is supplied with an opening 25. One of the studs 3 carries a resilient sleeve 50, adapted to serve as an abutment for the semaphore 22, should the lever end of the semaphore happen to swing inwardly beyond the position shown in Figure 1. A link 26 is pivoted at 27 to the second lever 15, at a point intermediate the ends of the lever. One end of the link 26 is received loosely in the opening 25 of the semaphore 22.

An angular latch lever 28 is fulcrumed at 29 on the plate 4 and includes a depending arm 30 responsive to the electro-magnet 9, the latch lever comprising an arm 31, adapted to cooperate with the member 20 of the lever 15, and with the flange 21, in a way to be pointed out hereinafter. One end of a spring 32 is attached at 33 to the plate 4, the opposite end of the spring being curved, as at 34 so as to bear upon the arm 31 of the latch lever 28. A pin 35 projects from the plate 4 and engages the spring 32 to hold the end 34 of the spring on the arm 31 of the latch lever 28.

Referring to Figure 1 suppose that the electro-magnet 9 is deenergized, the arm 31 of the latch lever 28 being swung downwardly by the spring 32, until the outer end of the arm 31 rests on the part 20 of the lever 15, behind the flange 21, the upper portion of the lever 15 bearing against one edge portion 36 of the semaphore arm 22, the semaphore arm being lowered, and being

held in the casing 1. Suppose, now, that the electro-magnet 9 is energized. Then, the electro-magnet attracts the arm 30 of the lever 28, the lever being swung on its fulcrum 29 and the arm 31 of the lever 28 being disengaged from behind the flange 21 of the lever 15. The lever 15, thus, is set free for inward swinging movement. When the electro-magnet 9 is energized, the lever 12 is attracted, and swings the lever 15 inwardly, the link 26 transmitting motion to the semaphore arm 22 and swinging the semaphore arm outwardly, into the position shown in Figure 2, thereby to cause the giving of a signal. So long as the electro-magnet 9 is energized, the parts will remain in the position shown in Figure 2, but as soon as the electro-magnet is deenergized, the parts will assume the positions shown in Figure 1.

The link 26 has a slight amount of play in the opening 25 of the semaphore 22. Consequently, when the magnet 9 is energized, the arm 31 of the lever 28 will be swung upwardly, out of engagement with the flange 21 on the lever 15, before swinging movement is transmitted to the semaphore 22 by the lever 12, the lever 15 and the link 26. As shown in Figure 4, the rear wall of the body 2 may carry a lens 37. A bracket 38 is mounted on the rear wall of the body 2 and carries a socket 39 wherein an electric lamp 40 is mounted, the plate 4 having an opening 41 giving access to the lamp. The lamp 40 and the lens 37 constitute a tail light. A lens 37^a is mounted in the lid 5, in alignment with the lens 37, and shows a for-

wardly presented signal, as distinguished from a tail light. The lenses 37 and 37^a may be red in color. They show when the arm 40 22 is raised, but are obscured when the arm is lowered, as shown in Figure 1.

Having thus described the invention, what is claimed is:

In a device of the class described, a support, oppositely extended first and second levers fulcrumed at their remote ends on the support, the first lever being engaged pivotally at its inner end with an intermediate portion of the second lever, a semaphore 50 mounted intermediate its ends to swing on the support, the semaphore, when in inactive position, being disposed alongside of the second lever and in close relation thereto, means for connecting an intermediate 55 portion of the second lever with one end of the semaphore, a bell crank latch fulcrumed on the support, one arm of the latch extending in the same general direction as the first lever, the other arm of the latch extending 60 transversely of both levers in close relation to the fulcrumed end of the first lever and cooperating with the free end of the second lever to hold the semaphore in inactive position, and an electro-magnet located between 65 the first-specified arm of the latch and the first lever, the first-specified arm of the latch being responsive to one end of the magnet to release the second lever, and the first lever being responsive to the other end of the magnet to move the semaphore to active position.

In testimony that I claim the foregoing as my own, I have hereto affixed my signature.

FRED R. BARBOUR.
